REFRIGERATING MACHINE

Original Filed Nov. 13, 1926

Inventor:

Christian Steensma

UNITED STATES PATENT OFFICE

CHRISTIAN STEENSTRUP, OF SCHENECTADY, NEW YORK, ASSIGNOR TO GENERAL ELECTRIC COMPANY, A CORPORATION OF NEW YORK

REFRIGERATING MACHINE

Application filed November 13, 1926, Serial No. 148,266. Renewed May 2, 1929.

My invention relates to electric refrigerating machines of the type especially adapted for domestic use and particularly to the construction and arrangement of the cooling unit 5 of such machines. An object of my invention is the provision of an improved cooling unit for such machines, and an arrangement of the same to cool the refrigerator cabinet and facilitate freezing articles therein.

16 My invention will be better understood from the following description taken in connection with the accompanying drawing, and its scope will be pointed out in the appended claims.

15 Referring to the drawing, Fig. 1 is a perspective view of a complete electric refrigerator having a cooling unit embodying my invention; Fig. 2 is a perspective view of the cooling unit drawn to a larger scale; Fig. 3 is a longitudinal cross sectional view of the cooling unit; Figs. 4 and 5 show respectively an ice cube tray and a rack for supporting the same in the cooling unit; Fig. 6 shows a modified form of plate for supporting the ice tray; Fig. 7 shows a modified form of cooling unit; and Fig. 8 shows a detail.

placed, to the refrigerant in chamber 8 will be more rapid than from the inside of the cabinet in which the cooling unit is arranged. In this way the temperature in the freezing chamber inside of the receptacle 5 is kept low enough to readily freeze water in the ice cube tray or other articles placed therein without reducing the temperature in the refrigerator cabinet below that desired to keep food or the like above the freezing temperature. The evaporator 9 is shown containing liquid refrigerant and passing through the outer chamber and the outer and intermediate receptacles are the inlet pipe 10 for liquid refrigerant and the outlet pipe 11 for evaporated refrigerant, the pipes being suitably connected with the condensing apparatus above. The mouth of the outlet pipe 11 is covered by the cap 12 which as shown more clearly in the enlarged detail view comprising Fig. 8 has large openings near the top and small openings near the bottom. By this construction if a layer of oil collects on the surface of the refrigerant during a shut-down a slug of oil will not be drawn up into the compressor upon starting the machine since

In Fig. 1 of the drawing I have illustrated an electric refrigerator adapted for domestic use and comprising the refrigerator cabinet or box 1 and the refrigerating machine of which the cooling unit 2 is located within the cabinet and the motor driven compressor and condenser 3 are supported on top of the cabinet. The cooling unit 2 shown more in detail in Figs. 2 and 3 comprises three cup-shaped steel receptacles 5, 6 and 7 nested one within another with adjacent walls spaced apart to provide chambers 8 and 9 therebetween, the inside of the receptacle 5 serving as a container for articles to be frozen. The inner chamber, which is the evaporator of the refrigerating machine used to cool the cabinet, contains refrigerant and the outer chamber contains a liquid whereby it functions as a heat reservoir. This outer chamber 9 is shown nearly filled with liquid which preferably is a freezing liquid such as a mixture of glycerine and water or brine, so that the heat transferred from the inside of the receptacle 7, wherein articles to be frozen are compressed upon starting the machine since the small openings 14 will limit the flow of oil to the compressor while the gas has a free flow through the larger openings 13. This arrangement functions in a similar manner to that disclosed and claimed in my copending application, Serial No. 109,960, filed May 18, 1926 and assigned to the same assignee as the present application. At their open ends the receptacles have their edges drawn together and welded for example by atomic welding. I preferably make the inner and intermediate receptacles cylindrical in form with their closed ends rounded whereby deformation of the receptacles due to pressure is less likely. The outer receptacle may also be cylindrical if desired but I prefer to make it somewhat rectangular so as to more economically use the space in the box allotted to the cooling unit. The cooling unit may conveniently be supported in the box by brackets 15 welded or otherwise secured to the outer receptacle. The open end of the cooling unit is closed by the detachable cover 16 having the handle 17 and a hook 18 at each side

which engages over a pin 19 on the outer receptacle.

One of the advantages of a refrigerator having artificial refrigeration is the ability and convenience with which small ice cubes may be frozen. These cubes are usually made in a pan such as shown for example in Fig. 4 where a shallow pan 22 preferably of good heat conducting material such as copper has loosely setting in it a group of equally spaced partitions 23 preferably of the same material. The pan for the sake of uniformity in the cubes has a flat bottom but such a pan when placed in the cylindrical inner receptacle of the evaporator will contact with the evaporator only along its two lower edges, all four sides being separated from the cold wall of the evaporator by a layer of air. Inasmuch as air is a relatively poor conductor of heat the rate at which heat is withdrawn from the water in the pan is relatively slow with the result that many hours may be required for the freezing of a pan of ice cubes. I have found that the length of time required to freeze a pan of cubes may be very materially lessened by providing a better thermal connection between the pan and the evaporator of the cooling unit which facilitates the conduction of heat from the pan to the cooling unit. This may be accomplished in various ways. In Figs. 2 and 3 I have shown the cooling unit provided with a barrier 25 extending across the mouth of the inner receptacle and serving as a dam to retain a small amount of freezing liquid 26 therein. This liquid may be plain water which will readily freeze solid or may be a liquid which will not freeze at the temperatures normally attained in the evaporator. For supporting the ice tray I have provided a rack or supporting member 27 comprising a plate 28 of metal or other suitable material of good thermal conductivity from which are punched curved ears 29 bent down to form supporting legs. The top of the rack when in position in the cooling unit is a little lower than the top of the barrier so that a sufficient quantity of freezing liquid may be added to cover the top of the rack. If the liquid used is water and has become frozen when the pan of water to be frozen is inserted, the warmth of the pan of water will melt a part or all of the ice overlying the rack, leaving the tray in good thermal connection throughout its bottom with the evaporator. The water from the ice melted from the top of the rack again freezes around the edges of the tray but is not sufficient to interfere with the subsequent removal of the tray.

Instead of providing the cooling unit with the barrier 25 to retain the freezing liquid I may use a removable shallow vessel, such as is illustrated at 30 in Fig. 6, the bottom of which is curved to fit closely the contour of the inner receptacle. The vessel is shown

provided with a number of transverse members 31 the top of which are slightly lower than the walls of the vessel for supporting the ice cube tray. When the vessel is filled with freezing liquid the liquid level will be slightly above the tops of the tray supporting members 31. Although actual contact between the vessel 30 and the evaporator of the cooling unit may not be uniform over the bottom of the vessel, due to unavoidable variations in the shape of the inner receptacle and of the vessel, it does not materially affect the rate of heat transfer for in service the entire evaporator becomes coated with a layer of frost so that when the vessel 30 containing water to be frozen is placed in the cooling unit the frost beneath the vessel first melts and then recongeals, thus providing a good thermal connection between the vessel and the evaporator of the cooling unit.

In some installations, as for example in hospitals, the chief function of the machine may be to freeze ice cubes and for this purpose it may be found more expedient to employ one or more flat plate cooling units such as shown in my copending application, Serial No. 109,960, filed May 18, 1926. In Fig. 7 I have illustrated such a cooling unit at 33 provided with an upstanding rim 34 forming therewith a shallow pan in which may be placed a little water or a non-freezing liquid. Ice cube trays placed on the frozen water or in the non-freezing liquid will thus have their bottom portions in good thermal connection with the cooling unit. It may not even be necessary to add water to the top of the cooling unit since sufficient moisture may have collected on the evaporator in the form of frost to provide the necessary water or ice connection between the ice tray and the evaporator.

As has already been pointed out, the freezing liquid contained in the outer chamber 9 functions as a heat reservoir, the liquid alternately freezing when the compressor is running and thawing when the compressor is idle, the operation of the machine being automatically governed in response to the temperature in the refrigerator box or in the freezing liquid or in part to both. The heat reservoir comprised by the body of freezing liquid makes the machine less sensitive to sudden and slight changes in temperature and causes the machine to start and stop at less frequent intervals than would be the case if such were not provided. The use of freezing liquid further increases the heat capacity of the reservoir since the heat of fusion is available in addition to the heat of the liquid.

In certain instances it may be desirable to provide for more refrigeration within the cooling unit than without it, for example if the user is more desirous of being able to freeze a large number of ice cubes than of

5 maintaining the usual low temperature in the refrigerator box. In such a case a certain amount of freezing liquid may be withdrawn from chamber 9 so that heat is less readily drawn from the box, the air space formerly occupied by freezing liquid serving as a heat insulator.

What I claim as new and desire to secure by Letters Patent of the United States, is:

10 1. In combination with a refrigerator cabinet, a cooling unit therein comprising an inner chamber for receiving articles to be frozen, an outer closed chamber surrounding the inner chamber and adapted to contain a liquid, an intermediate evaporator chamber adapted to contain a refrigerant, and means for circulating the refrigerant through said evaporator chamber:

15 2. In combination with a refrigerator cabinet, a cooling unit therein comprising a plurality of cup-like receptacles nested one within the other, adjacent receptacles being spaced from each other to form chambers surrounding the inner receptacle, the edges 25 of the mouths of said receptacles being formed of such size as to closely fit one within the other, means for securing said edges together, a liquid in one of said chambers, and means for supplying refrigerant to an other of said chambers.

30 3. In combination with a refrigerator cabinet, a cooling unit therein comprising a plurality of cup-like receptacles nested one within the other, adjacent receptacles being spaced from each other to form chambers surrounding the inner receptacle, the edges of the mouths of said receptacles being formed of such size as to closely fit one within the other, and means for securing said edges together.

35 4. In combination with a refrigerator cabinet, a cooling unit therein comprising a plurality of cup-like receptacles arranged one within the other and spaced apart to form a surrounding chamber, the edge portions of the mouth of said receptacles being formed of such size as to closely fit one within the other and firmly secured to one another to thereby close said chambers, said inner receptacle being adapted to receive articles to be frozen, and a detachable cover for said inner receptacle.

45 5. In combination with a refrigerator cabinet, a cooling unit therein comprising a cylindrical inner receptacle, a cylindrical intermediate receptacle spaced therefrom to form a refrigerant chamber, an outer receptacle spaced from the intermediate receptacle to form a heat reservoir chamber, and inlet and outlet pipes passing through the latter chamber and communicating with the refrigerant chamber, said receptacles being welded together at their edge portions.

60 6. In combination with a refrigerator cabinet, a cooling unit therein comprising a re-

ceptacle adapted to support an ice tray, said receptacle being provided with means for retaining a freezing liquid whereby said tray when in position is in good thermal connection with the evaporator.

70 7. In combination with a refrigerator cabinet, a cooling unit therein comprising a receptacle adapted to receive an article to be frozen, an evaporator surrounding the receptacle, said receptacle being also adapted to retain a body of freezing liquid therein, and means for supporting the article to be cooled with its lower portion immersed in said liquid.

75 8. In combination with a refrigerator cabinet, a cooling unit therein comprising a cylindrical receptacle, an evaporator surrounding said receptacle, said receptacle having means adapted to support a flat bottomed ice cube tray therein and for retaining a freezing liquid in contact with the tray.

80 9. In combination with a refrigerator cabinet, a cooling unit arranged in said cabinet and forming a horizontal cylindrical receptacle for receiving articles to be frozen, said cooling unit including an evaporator surrounding said receptacle and a closed chamber containing a freezing liquid surrounding said evaporator, means arranged in said cylindrical receptacle conforming to the curved bottom thereof and having a flat upper surface adapted to conform to the bottom of a flat freezing tray so as to form a good thermal connection therewith, and means for circulating a refrigerant through said evaporator.

90 10. In combination with a refrigerator cabinet, a cooling unit arranged in said cabinet and forming a horizontal cylindrical receptacle for receiving articles to be frozen, said cooling unit including an evaporator surrounding said receptacle and a closed chamber containing a freezing liquid surrounding said evaporator, means for retaining a body of liquid in the bottom of said receptacle in contact therewith so as to provide a good thermal connection with the bottom of a flat freezing tray, and means for circulating a refrigerant through said evaporator.

105 In witness whereof, I have hereunto set my hand this 11th day of November, 1926.

CHRISTIAN STEENSTRUP.

DISCLAIMER

1,755,084.—*Christian Steenstrup*, Schenectady, N. Y. **REFRIGERATING MACHINE.**
Patent dated April 13, 1930. Disclaimer filed April 13, 1931, by the assignee,
General Electric Company.

Therefore, enters this disclaimer to claims 2 and 3 of said patent which are in the following words:—

“2. In combination with a refrigerator cabinet, a cooling unit therein comprising a plurality of cup-like receptacles nested one within the other, adjacent receptacles being spaced from each other to form chambers surrounding the inner receptacle, the edges of the mouths of said receptacles being formed of such size as to closely fit one within the other, means for securing said edges together, a liquid in one of said chambers, and means for supplying refrigerant to another of said chambers.

“3. In combination with a refrigerator cabinet, a cooling unit therein comprising a plurality of cup-like receptacles nested one within the other, adjacent receptacles being spaced from each other to form chambers surrounding the inner receptacles, the edges of the mouths of said receptacles being formed of such size as to closely fit one within the other, and means for securing said edges together.”
